UNITED STATES PATENT OFFICE.

JOEL SMITH, OF MORAN, MICHIGAN.

TYPEWRITER.

Application filed December 19, 1922. Serial No. 607,854.

To all whom it may concern:

Be it known that I, JOEL SMITH, a citizen of the United States, and a resident of Moran, in the county of Mackinac and State 5 of Michigan, have invented certain new and useful Improvements in Typewriters, of which the following is a specification.

My invention relates to improvements in typewriting machines (or typewriters, as 10 such machines are commonly called), and it consists of the constructions, combinations and mode of operation herein described and claimed.

An object of the invention is to provide a 15 typewriter which is capable of producing printed matter in any one of a plurality of styles of type, or producing such printed matter in a mixture or combination of such various styles of type.

20 A further object, expressed more in detail, is to provide a typewriter which can be set to print lower and upper case letters in any one of a number of styles of type which it contains, but which may so readily be shifted that words, lines or sentences written in letters of another type style may be interpolated for the purpose of emphasis, etc., in the matter which is being written under the original setting of the machine.

25 A further object of the invention is to provide in the foregoing machine, a style indicator so that the operator may know at a glance what style of type he has in the printing position.

30 Other objects and advantages will appear in the following specification, reference being had to the accompanying drawings, in which:

Fig. 1 is a plan view of the improved 40 type writer showing the setting of the type bars in segments both in front and rear of the printing platen, also disclosing other features of the invention for the understanding of which reference must be made to the accompanying description.

Fig. 2 is a longitudinal section of the typewriter (which might be considered as taken substantially, but not accurately, on the line 2-2 of Fig. 1) clearly showing 50 some of the important working parts of the machine.

Fig. 3 is a detail section taken substantially on the line 3-3 of Fig. 1, showing the case shift lever and its associated parts 55 only,

Fig. 4 is a detail plan view of the type style indicator in Fig. 1.

Fig. 5 is a front view of the type bar guide through which the type bars pass as they strike the platen in the operation 60 of printing, and

Fig. 6 is a detail cross section on the line 6-6 of Fig. 5.

Generally speaking, this typewriter is so arranged that the operator may make an 65 adjustment to write in any one of several styles of type. For example, the present typewriter has type in both large roman and italic styles. By making the proper adjustment, the typewriter will write in 70 large roman style and by using the customary shift key will produce capital letters in that style.

The typewriter is also capable of writing 75 in italic style, but instead of arranging the mechanism in such a way as to render the necessary adjustments for writing in either one of the two styles permanent, provision is made to permit the operator to shift from one type style to another as readily as he 80 shifts from lower case (small) to upper case (large) letters of the roman style. This is a feature that has obvious advantages. One may desire to emphasize some particular portion of the text under production. 85

The typewriter may be set to produce 90 printed matter in roman style. The operator may desire to set off or emphasize certain foreign words, phases, or even sentences. This is accomplished by the very convenient and effective shifting to the italic style, and words, etc. written in this style and interpolated in the roman style of type, will receive the proper recognition intended 95 by the author. With this brief introduction in mind, the reader may consider the details of the machine, which details are described under major subjects.

The frame comprises a casting 1 which 100 is the foundation by which all of the other structure is supported. The frame has lugs or ears 2, only partly shown in Fig. 1, and a little more clearly shown in Fig. 2, for the purpose of providing means to grip the frame so that it may be conveniently lifted. 105 The frame also has feet 3 adapted to carry the usual pads to rest on the desks.

A bridge 4 and supporting bar 4^a extend 110 from one side of the frame to the other. The bridge 4 furnishes the support for the

bearings 5 of a style shift bar 6 which extends from the left side of the machine to the center (Fig. 1) where connection is made with the type basket 7. For this purpose, 5 the bar 6 carries an arm 8 and the type basket has a link 9. The two have pivotal connection as shown in Fig. 2 and the link 9 is joined to a lug 10 on the type basket. Upon depression of the case shift key 11, 10 the printing platen will be moved rearwardly (toward the left in Fig. 2) so as to print capital letters in roman style.

The printing platen 12 being perhaps more closely associated with the frame 1 than with any other part, is therefore described under this subject. It is mounted on a carriage 13 (Fig. 2) which is merely indicated in dotted lines so as to disclose its general location. The carriage is adapted 20 to run on a travel way 14, which in turn is adapted to move longitudinally of the frame between the front stop 15 (furnished by a part of the frame 1) and the back stop 16. This longitudinal movement of the 25 travel way is accomplished by the case shift key 11, and obviously, moving the travel way as described, will move the printing point in relation to the frame so that a capital character which otherwise misses the 30 printing point, will then strike it.

Fig. 3 illustrates how the carriage travel way 14 is shifted. A shaft 17 runs crosswise of the frame and is supported in bearings 18 at the ends. Adjacent to each end, the 35 shaft 17 carries a bell crank (only one being shown in the drawings) having a vertical arm 19 and a horizontal arm 20. The one connects with a lug 21 on the underside of the travel way 14, while the other connects 40 with a link 22 in turn connected at 23 to the lever 24 of the case shift key 11 mentioned before. A block 25 supports a link 26 which has pivotal connection with a bearing 27 adjacent to the rear edge of the travel-way. 45 This link is necessary to assist in supporting the travel-way.

A four-point suspension is furnished to the travel-way 14 by the bell crank and link connections just described, it being understood 50 that the duplicate of the arrangement in Fig. 3 occurs on the opposite side of the frame which would be at the right in Fig. 1. It seems an obvious expedient to provide a three-point suspension by employing the 55 same arrangement disclosed in Fig. 3, with the exception that only one link 26 would be used and in such case the link should be situated to support the travel-way in the center at the rear edge and thus take a position at one of the three points of a triangle. 60

A spring 28, connected between the arm 19 and a bracket 29 on the bottom of the frame, keeps the travel-way 14 in normal contact with the front stop 15 of the frame. 65 A spring 30 (Fig. 3, right end) keeps the

shift lever 24 normally up. One end of the spring is suitably secured to the spring bar 31, while the other end has a suitable connection to the shift lever.

There is another shift lever at the right 70 side of the machine so that a shift from lower case to upper case characters may be accomplished from either side of the frame. This other shift lever is designated 32 in Fig. 1. As stated before, it has operating 75 connections with the travel-way 14 identical to those shown in Fig. 3. Both shift levers are connected to a cross bar 33 at the rear of the frame. This cross bar is journaled to a bearing block 34, and the cross 80 bar is situated below the common pivot rod 35 of the typewriter key levers 36 of which there are forty-two, as shown in Fig. 1.

The case shift lock down had best be described in connection with the case shift key 11 and shift lever 24 in Fig. 3. Its purpose is to hold the carriage travel-way 14 back against the stop 16 so as to retain the correspondingly shifted position of the printing point should the operator desire to 90 write in upper case characters for any prolonged period. By use of the shift lock the printing platen 12 is held in the rearmost position so that upper case or capital letters 95 of any of the type styles in which the machine is capable of writing and for which it may be adjusted, may appear at the printing point.

This shift lock down is very simple. The shank 37 of the key (Fig. 3) has a hinge 100 connection 38 with the front end of the lever 24. The shank includes a catch 39 which, in an ordinary depression of the shift lever, avoids the shoulder 40 (Fig. 1) of the locking block 41. But upon turning the shank 105 37 toward the left (Fig. 1), having first depressed the shift key, the catch 39 is moved under the shoulder 40 and so holds the shift key and lever down.

To facilitate the turning of the shank 37, 110 the key 11 includes an upturned flange which terminates in abutments 42 on each side at the front. These are useful in taking the side thrust of the finger in either moving the shank 37 toward the left (as stated) to 115 obtain the lock down, or toward the right to release the latch 39 from the shoulder 40. The shift key 11 is kept in the desired normal position (Fig. 1) on the shift lever 24 by a spring 43 (Fig. 3) which has connection between a lug 44 on the key and a lug 45 on the lever. Another small lug 46 (carried by the key) is arranged to engage the side of the lever near the top edge, as shown in Fig. 3, to limit the turning movement of the shank 37 under the influence of the spring. It will become obvious later that the foregoing lockdown means may be applied to the style shift lever as well as to the case shift lever, although the drawing 120 125 130

is confined to showing the latter application.

The type bar system should be considered next. The type basket 7 is a necessary element of the type bar system in that it not only furnishes a protecting casing around the type bars but also provides a means of support therefor. The type basket is of a generally oblong shape, including parallel side arms 47 and semi-circular ends 10 which are made in this shape to conform to the configurations of the front and rear type bar segments 48 and 49.

Each of the type basket side arms 47 moves loose beside the bridges 50 which are 15 an integral part of the frame 1 and form the connections between the lower and foremost parts thereof with the yoke 51 at the rear. Portions of the upper surfaces of the bridges are faced at 52 to provide races for 20 anti-friction bearings 53 carried by suitable containers 54 which rise from the side arms 47 with the general appearance of lugs.

A cover 55 (Fig. 1) keeps dust and dirt 25 out of certain bell crank connections of the type bar system at the rear of the basket. Only one of these covers is shown in Fig. 1 but there is another one like it (in actual practice) on the left side of the center of the machine. The cover is fastened down 30 on the yoke 51 by screws 56, and it includes a strong catch 57 which extends down and engages the under side of the adjacent bridge 50. The covers assist in holding the type basket to its bearings.

35 A similar arrangement of anti-friction bearings occurs at the front of the type basket. Upward extensions 58 (Fig. 1) furnish bearing surfaces for the anti-friction bearings 59 carried by forward extensions 40 60 of the type basket. The upward extensions 58 have lugs 61 at the front and lugs 62 at places adjacent to the type basket. The extensions 60 have stops 63 which move between these lugs and so limit the forward 45 and rearward movements of the type basket.

Mention should also be made of the fact 50 that other parts of the type bar system at the front of the typewriter are protected by covers 64. In Fig. 1, one of these is shown 55 in place, the other being removed so as to reveal the location of such parts. These are described below. A cover 65 protects the rear ends of the typewriter key levers, especially the places where they are pivoted on the rod 35.

Only one type bar is shown in each of 60 the type bar segments 48 and 49 in Fig. 2, and this for simplicity in illustration. The respective type bars are designated 66 and 67 respectively. Each terminates in a head 65 68 and 69 respectively, the former having capital and small printing characters 70, 71, 72 and 73, the latter having small and capital type printing characters 74, 75, 76 and 77.

Taking these characters in the order

named, there are first, the capital "H" and small "h" (70 and 71) in roman style. Next, the capital "H" and small "h" (72 and 73) in italic style. These occur in the front segments. In the rear segments, there 70 are the small "p" and capital "P" (74 and 75) in italic style, and small "p" and capital "P" (76 and 77) in roman style. The reader will have observed that both the order of the characters and their styles are 75 reversed (reading down from the top) in the two type segments.

This arrangement or reversal of the order of the printing characters and type styles in the front and rear type bar segments is made 80 necessary to accommodate the rearward movement of the printing platen 12 upon a case shift. The printing point is designated by the arrow P in Fig. 2. According to the present adjustment of the typewriter, 85 a depression of the proper printing key will depress the type bar 66 and print the small "h" 71 in roman style (follow the heavy dotted line 78).

Under the same adjustment of the typewriter, the depression of another printing key will move the type bar 67 to print the small "p" 76 in roman style (follow the dotted line 79). Should the operator now desire to print capitals or upper case letters 90 70 and 77 in roman style, the case shift key 11 must be depressed to move the platen 12 rearwardly so as to shift the printing point to the place P'. By following the light dotted lines 80 and 81 respectively, 95 the reader will see that the paths of the characters "H" and "P" (70 and 77) fall to the left of the paths of the corresponding small characters, as is made necessary so that they may reach the new position of the 100 printing point which has also shifted to the left.

In calculating the positions of the printing characters on the type bar heads, the 105 lines 78 and 79 are taken as a basis in normal printing and the capital or upper case characters of the lower case characters traversed by said lines are situated as far above and below said characters in segments 48 and 49, as the printing point P' is shifted 110 from the normal printing point P upon a case shift. In other words, the capital "H" 70 and the capital "P" 77 are as far above and below the corresponding small letters 71 and 76 as the shifted printing point P' 115 is from the printing point P. The identical principle prevails in the arrangement of the characters in the italic type style, but as printing in this style involves shifting the type basket 7, the description of the operation thereof is reserved to the place under the "The Style Shift" heading below.

The type bars in the respective front and rear segments 48 and 49 are mounted on pivots 82 and 83. A link 84, connected at 120

85 above the pivot 82 of the type bar 66, produces a downward stroke of that type bar upon a downward movement. The link 84 has direct connection with an appropriate 5 one of the key levers 36.

A link 86 has a pivotal connection 87 with the type bar 67 at the rear of the machine and at a point below the pivot 83, and an 10 upward movement of the link causes a downward stroke of the type bar 67 to the printing position.

But instead of being connected directly to a key lever as in the case of the link 84, the link 86 receives its motion through two 15 bell cranks 88 and 89 and an intermediate link 90, the latter bell crank having a link connection 91 (corresponding to the link 84) to an appropriate one of the key levers 36.

20 Anticipating that promptness of return movement of the type bars 67 in the rear segment 49 may be sacrificed by the pivotal connections of operating parts between the type bars 67 and the appropriate key levers, provision is made of a spring 92 for each of 25 the type bars in said rear segment. The spring 92 (there being one for each type bar in the rear segment) is connected between a crank extension 93 of the bell crank 30 88 and a bracket 94 on the rear of the type basket 7. The tendency of this spring is to pull down on the bell crank 88, and by tracing the connections, the reader will see that the ultimate tendency is to push the type 35 bar 67 to the erect position.

40 Pads 95 and 96 in the front and rear segments respectively, receive the return thrusts of the type bar heads 68 and 69 and serve to reduce the sound of contact. These pads are mounted on metal strips 97 and 98 which, in turn, may be made removable so 45 that the pads may be replaced when necessary. The type bar heads are impelled back to position against pads 95 and 96 chiefly by the springs 30 (Fig. 1) which operate near pivotal bearings of key levers 36 to return these levers to rest position.

50 Fingers 99 and 100 guide the type bars 66 and 67 of the front and rear segments during the downward and upward strokes. These fingers are nothing more than arcuate metallic strips which divide the spaces between the type bars. To further guide the type bars, insure an absolutely accurate 55 printing impression, and prevent vibrations of the type bars, the provision of a substantially central type bar guide 101, is made. This type bar guide is placed as near to the center (in reference to the pivots 82 and 83 60 and the printing platen 12) as the printing point will allow. Being located off center, the type bar guide 101 will make engagement with the type bar 67 of the rear segment 49 at a place adjacent to the base of 65 the head 69, as shown by the dotted line

position of the depressed type bar. As it is obviously impossible that a similar place of engagement of the type bar 66 in the front segment 48 may be made with the guide 101, said type bar is provided with a key 102 at 70 the upper extremity of the head 68 to serve the purpose under consideration.

The type bar guide 101 has the general shape of a V, as is to be seen in Fig. 5. But in order to produce a more rapidly narrowing passage than a straight-sided V would provide, the inner edges of the guide 101 are convexly curved as shown. The guide has flanges 103 at the top for the purpose of fastening to the adjacent side arms 47 of the movable type basket 7. The lower ends of the guide are connected by a bridge 104, but this bridge is so located as not to conflict either with the type bar 67 of the rear segment or the key 102 of the front 25 segment.

For the purpose of furnishing a complete description of the type bar system, it is necessary to say that the bell cranks 88 and 89 (Fig. 2) of the rear and front segments respectively, are divided into two sets of ten each. These bell crank sets occupy positions at the sides of the center of the machine (see Fig. 1). Of necessity, the various bell crank sets have bearings 105 and 106 respectively. The top connecting links 90 cross the machine according to the arrangement in Fig. 1, connecting corresponding bell crank sets of the two segments as are located diametrically opposite to each other. It will be noted in Fig. 2 that certain ones of the upwardly extending bell crank arms are longer than others. It is necessary to make them so in order that the top links may cross as described. The foregoing description deals with a detail of construction of the typewriter, and this has no particular bearing on other features of the invention which are regarded as more important.

105 The style shift occurs when the type basket 7 is moved rearwardly. The style of writing then changes from large roman to italic. All of the type bars in the two segments 48 and 49, and all connecting links and bell cranks move with the type basket 7 as a unit. The printing platen 12 remains where it is unless the operator desires to print capital letters, whereupon the case shift key 11 is 110 depressed, as before.

115 All this is accomplished either by depressing the style shift key 107 or moving the crank 108 (Fig. 2) to the forward end of the arcuate slot 109. The first act furnishes a mere temporary adjustment of the type basket 7 to the italic style which adjustment remains only so long as the operator keeps the key 107 depressed. The second act furnishes a prolonged adjustment of the typewriter to the changed type style, which re- 120

mains until the crank 108 is turned back to the position now shown in Fig. 2.

The first or temporary adjustment is made when the operator desires to interpolate in text written in large roman style, certain words, phrases, or portions of printed matter which it is desired to emphasize or offset from the rest of the text. The second adjustment is made when it is desired to write 10 all of the text in italic style, and under such adjustment the style shift key 107 will function precisely as before, i. e. it will operate to temporarily reversely shift the type basket 7 so that words, etc., may be interpolated 15 in large roman style in the italic style text.

Consider the construction: A bar 110 rocks on the same pivot which supports the style shift bar 6; in fact, the rocker bar 110 may be considered an integral part of 20 the bar 6. The rocker carries pendent links 111 and 112 at its ends. These terminate in hooks 113, 114 which partly embrace the lever 115 of the style shift key 107.

The style shift lever has shoulders 116 25 and 117 at the front and rear respectively, considering them in reference to the perpendicular location of the style shift bar 6. The hooks are connected by a link 118 which insures a parallel motion. When assuming 30 one position (as in Fig. 2) of the rocker bar 110, the hook 114 lies in the path of the rear shoulder 117, while the hook 113 is out of the path of the front shoulder 116. Upon reversal of positions, the hook 113 will be 35 in the path of the front shoulder 116 while the hooks 114 will be out of the path of the rear shoulder 117.

This change in position of the hooks in 40 reference to the shift lever shoulders determines whether the type basket 7 shall be shifted rearwardly or forwardly upon a depression of the style shift key 107. Take the adjustment as it now is in Fig. 2: A depression of the style shift key 107 will cause 45 the type basket 7 to be shifted rearwardly. The reader can readily see this by tracing the various connections from the engaging shoulder 117. Should the type basket 7 occupy the prolonged rearward shifted position such as is brought about by turning 50 the crank 108 forwardly in the slot 109, a depression of the key 107 would shift the type basket 7 forwardly because the hook 113 would then be in position beneath the 55 forward shoulder 116.

An operating bar 119 extends between the crank 108 and a bearing block 120 on the bottom of the frame. This block has a vertical slot 121 so that the stud 122 of the 60 bar may ride up and down when the crank 108 is turned from the rear end 123 of the slot 109 to the front end 124. This bar occupies a space between lugs 125 on the link 118, and it is through engagement with one 65 or the other of these lugs that the hooks 113

and 114 are made to shift in respect to the style shift lever shoulders accordingly as the crank 108 is turned.

Turning or shifting the crank 108 changes the tension of the springs 126 and 127. 70 These springs are connected between a disk 128 on the crank and the extremities of an arc 129 which forms part of a bracket 130 carried by the rocker bar 110. When the crank 108, is in the rearward position, the 75 spring 126 is expanded and the type basket 7 is held in the forward position because the direction of the tension of the spring 126 is diagonally upward toward the left and under the pivot of the style shift bar 6. 80 When the crank 108 is shifted forwardly, the spring 127 will be expanded and the type basket 7 will be held in the rearward position because the direction of the tension of the spring 127 will be diagonally 85 upward toward the right under the pivot of the bar 6.

It is therefore largely a matter of tension in one or the other of the springs 126 and 127 that determines the forward or rearward position of the type basket 7. Obviously a depression of the style shift key 107 will act against such spring as is then under tension. For example, a depression 90 of the style shift key 107 under the present 95 adjustment will rock the bar 110 counterclockwise and thus convey the lower right extremity of the arc 129 farther toward the right. This will increase the tension of spring 126 and this increase of tension 100 serves to return the type basket 7 to the original position when the key 107 is released. The reverse operation occurs in respect to the spring 127 and key 107 when the type basket 7 stands in a more permanently 105 shifted position by virtue of changing the crank 108.

The type style indicator is an important part of the style shift apparatus, in that it shows at a glance which of the two type 110 styles are in printing position at any given time. The indicator is shown in position in Fig. 1, and Fig. 4 shows it more in detail. The type basket 7 carries a plate 131 which has the legends "1a. Rom." 132 and "Italic" 115 133 printed thereon. The former is the abbreviation for "large roman" and indicates one of the two styles of type. This plate, being affixed to the type basket, necessarily moves back and forth with corresponding movements of the type basket.

Affixed to an adjacent part of the bridge 4 is a covering plate 134 having an opening 135 in such a position as to reveal either of the legends referred to, according to the 120 position of the type basket. The operator has only to glance at the covering plate to see whether the typewriter is adjusted for 125 writing either in large roman style or italic style. 130

The operation may be briefly reviewed so that the reader may have the substance of the foregoing description before him in condensed form. The typewriter as herein disclosed, is capable of printing text in either or both of two type styles. The type styles adapted for illustration are large roman and italic. In Fig. 2 (at the right), 70 and 71 are the upper and lower case letters in large roman style, while 72 and 73 are the corresponding letters in italic style. A corresponding arrangement of styles and the order of letters is maintained in all of the type bars of the segment 48.

There are two of these segments, one at the front, the other at the rear. The rear segment 49 has type bars in which both the order of the characters and of the styles are reversed. 74 and 75 are the lower and upper case letters in italic style, while 76 and 77 are the corresponding letters in roman style. This reversal of order and style is made necessary to reach the printing point either in its original position P or shifted position P'.

To print lower case or small letters in roman style: the typewriter is used without changing any of the present adjustments in Fig. 2. The operator depresses the shift levers 36 (Fig. 1) as in any other typewriter. A downward stroke of the type bar 66 (Fig. 2) will move the small character 71 along the dotted line 78 until the printing point P is reached. All other lower case letters in large roman style and in the front segment 48 will traverse a similar path. The letter 76 of the type bar 67 will traverse the path 79, and so will all other lower case letters in roman style in the rear segment 49. None of the other letters represented will strike at the printing point under the present adjustment of the typewriter, as is perfectly obvious by referring to the dotted line position of the rear type bar 67.

To print upper case letters in roman style: press the case shift key 11. This shifts the travel-way 14 (Fig. 2) against the back stop 16 and shifts the printing point on the platen 12 a corresponding distance. The shifting of the travel-way is accomplished by the bell cranks 19 and 20 and link 22 in Fig. 3. Operate the key levers 36 as before. Either the upper case characters 70 (in the front segment 48) or 77 (in the rear segment 49) will now traverse the path 80 or 81 and reach the shifted printing point P'. The reader should bear in mind that the printing platen 12 is moved in reference to the type bars in order to shift from lower case to upper case character printing.

To temporarily change from large roman to italic style printing: this facility of the typewriter is taken advantage of only at such times when the operator desires to in-

terpolate words, etc., in italic style in the roman style text which the typewriter is presumed to be printing. The printing platen 12 remains where it is in Fig. 2 when the operator desires only to have the interpolated matter appear in lower case italic. For example, to print the lower case italic 73, depress the style shift key 107. The shift lever 115 will (through the shoulder 117 and hook 114) rock the bar 6 to move the type basket 7 rearwardly until the pivot 82 assumes the position a (Fig. 2) and the pivot 83 assumes the position b. A depression of the appropriate typewriter key will move the character 73 along dot and dash lines 136 until it reaches the printing point P. Similarly, the depression of the aforesaid key will move the lower case italic letter 74 in the rear segment 49 along the dot and dash line 137 until it too reaches the printing point P. The aforesaid depression of the style shift key 107 is against the tension of the spring 126. This spring already is under tension and is the medium whereby the type basket 7 is held in the forward position shown. The additional tension under which it is put upon depression of the key 107 merely serves to return the type basket to the original position when the key 107 is released.

To temporarily print capital italics while the machine is under adjustment for printing in roman style, press both the case shift key 11 and the style shift key 107. This shifts the printing platen 12 back to a position beneath the shifted printing point P'. It also shifts the type basket 7 until the pivots 82 and 83 assume the positions a and b. A depression of the appropriate key will move the upper case italic 72 along the dot and dash line 138 until it reaches the shifted printing point P', while the depression of the appropriate key of a type bar in the rear segment 49 will move the upper case italic 75 along the dot and dash line 139 until it reaches the shifted printing point.

As long as both keys 11 and 107 remain depressed, the machine will write in upper case italic. Releasing these keys will restore the printing platen 12 to the forward position and the type basket 7 to the forward position so that lower case writing in roman style may be resumed.

To continuously print in italic style: the position of the crank 108 must be reversed until it assumes a position in the front end 124 of the circular slot 109. This changes the tension of the springs, putting the spring 127 under tension and relaxing the spring 126. This causes the style shift bar 6 to rock so that the arm 8 changes its inclination toward the left and causes the type basket 7 to move rearwardly until the stops 63 (Fig. 1) engage the lugs 62. The printing platen 12 remains where it is. The pivots

82 and 83 now permanently assume the positions *a* and *b*, and by tracing the paths of the lower case italic letters along the lines 136 and 137, the reader will see that nothing but small letter text will appear at the printing point P.

The shifting of the crank 108 also shifts the positions of the hooks 113 and 114, the former now being under the shift lever 10 shoulder 115. The hook 114 which was active in the preceding description, now assumes a position to the right of the shoulder 117, and a depression of the style shift lever 115 will have no effect upon the hook 114.

To interpolate roman style printing in italic style text: if the operator desires to write one or more words in lower case roman style while the typewriter is adjusted for continuous italic style printing, the style shift lever 115 should be depressed to cause the type basket 17 to move forwardly into its original position, as in Fig. 1. This is done against the further tension of the spring 127, and a release of the key 107 will cause the basket 7 to move back to its rearward position. The effect of the forward shifting of the type basket is to permit printing of lower case characters 71 and 76 in roman style at the printing point P (follow lines 78 and 79).

To print upper case letters in roman style while the machine is adjusted for continuous italic style printing: depress both keys 107 and 11 at once. This again shifts the type basket 7 forwardly against the tension of spring 127, and shifts the printing platen 12 rearwardly until it comes under the shifted printing point P'. By following the dotted lines 80 or 81, the reader will see that the depression of the appropriate keys will carry the upper case roman style characters 70 and 77 down to the printing point P' and thus interpolate upper case roman style printing in the italic style text, as long as pressure remains on the keys 107 and 11.

The reader now understands that the case shift key 11 is used whenever the operator desires to print upper case characters in either of the two styles, roman or italic. According to the foregoing description, pressure must be maintained on both keys 107 and 11 if the interpolated upper case matter is to be continuous. As this, under some circumstances, might easily prove an arduous task, provision is made of the shift lever lock-down mechanism described in connection with Fig. 3. By the use of this mechanism the case shift lever 24 of the key 11 may be held down for a prolonged period and the operator need only to maintain pressure on the key 107 to keep the type basket 7 to the front. It can also be seen, by having on the style shift lever the same lock down construction as is on the case

shift lever, which may be preferable though not shown in the drawings, by a slight turn of the key 107 it may be held down, the operator being free to use both hands in a lengthy insertion of matter in another style 70 of type.

This lock down consists of nothing more than a hinged arrangement of the shank 37 of the shift key 11. The shank has a latch 39 which ordinarily avoids the shoulder 40 75 (Fig. 1), but upon depressing the key 11 and giving it a side motion toward the left (Fig. 1) the latch 39 is brought in position under the shoulder 40 and remains there by friction until the key is given a reverse motion 80 to release it from said shoulder.

While the construction and arrangement of the improved typewriter as herein described and claimed, is that of a generally preferred form, obviously modifications and 85 changes may be made without departing from the spirit of the invention or the scope of the claims.

I claim:—

1. A typewriter having a platen, a type 90 bar, upper and lower case printing characters in a plurality of type styles carried by the bar, means in which the type bar is mounted to operate to normally print lower case characters of one type style, a frame 95 supporting said mounting means, means to shift said mounting means in respect to the frame to accordingly change the normal position of the type bar and move another one of said type styles in the position of registration 100 with the printing point on the platen, and means to shift the platen in either condition of the mounting means and type bar to permit upper case character printing.

2. A typewriter comprising a frame, a 105 platen supported by said frame, a type bar having upper and lower case printing characters in a plurality of type styles, a pivotal support for the type bar, a type basket on which the pivotal support is mounted and 110 upon which it is adapted to swing to the printing position, means supporting the type basket upon the aforesaid frame, means to shift the type basket upon said supporting means in respect to both the aforesaid frame 115 and platen to in turn shift the normal position of the type bar in respect to the platen and change the style of lower case type registrable with the printing point, and means to shift the frame and platen in respect to 120 the type basket to permit upper case character printing.

3. A typewriter comprising a frame, a platen, a type bar having upper and lower case printing characters in a plurality of 125 type styles, a type basket supported on the aforesaid frame and in which the type bar is mounted to operate, means to shift the type basket upon said frame in respect to the platen to change the style of lower case 130

type registrable with the printing point, and means to shift the platen in respect to said frame and said type basket for the printing of upper case characters in any of 5 the type styles, both of said shifting means being operable either severally or in unison to produce corresponding shiftings of the type basket and platen.

4. A typewriter comprising a frame, a 10 platen supported by said frame, a type basket supported upon said frame, a type bar mounted to operate on the type basket and having upper and lower case characters in a plurality of type styles, the lower case 15 characters of one style being in normal registration with the printing point; means to shift the type basket in respect to both the frame and platen to bring the lower case characters of another type style in registration 20 with the printing point, and means to shift the platen in respect to the frame either during or after any shifting of the type basket to bring the upper case characters of any type style in registration with 25 the printing point.

5. A typewriter comprising a frame, a platen supported by the frame, a type basket supported by the frame, a type bar carried by the basket and having printing 30 characters in a plurality of type styles, a plate carried by the type basket bearing legends designating the several styles of type on the type bar, and a covering plate carried by the frame having an opening with 35 which that one of the styles of type in the printing position at a given adjustment of the type basket is adapted to register.

6. A typewriter comprising a frame, a platen supported by the frame, a type bar 40 having printing characters in a plurality of type styles, a type basket supported on the frame and carrying the type bar, a tensioning device mounted on the frame which is adjustable to maintain the type basket in 45 any one of a plurality of positions on the frame corresponding in number to that of the type styles, so that any one of said type styles may be in registration with the printing point on the platen, and means to shift the platen in respect to the type basket in 50 any one of said positions so as to accordingly shift the printing point in respect to the type style then in registration.

7. A typewriter comprising a frame, a platen supported by the frame, a type basket supported by the frame and movable in respect to the platen, a type bar carried by the basket having printing characters in a plurality of type styles, a tensioning device 55 mounted on the frame and including a plurality of springs adapted to individually exert a moving influence on the type basket, means to put predetermined ones of the springs under tension to accordingly move the type basket and maintain a corre-

sponding type style in registration with the printing point, and a key to shift the type basket on the frame to bring another type style in registration with the printing point thereby increasing the tension of the spring 70 already under tension, said increased tension restoring the type basket to the former position upon release of the key.

8. A typewriter comprising a frame, a platen supported on the frame, a type basket supported by the frame, a type bar carried by the basket and having printing characters in a plurality of styles, a tension device including a pair of springs, connecting means between the springs and the type basket, and means to put one or the other of the springs under tension to correspondingly move and maintain the type basket either in a forward or rearward position on the frame and thus bring one or the other 80 of said type styles into registration with the printing point on the platen; and a key lever to shift the type basket from either occupied position against the spring already under tension to bring the other type style 85 into registration with the printing point.

9. A typewriter comprising a frame, a platen supported by said frame, a type basket supported by the frame, a type bar carried by said basket having upper and lower 90 case characters in a plurality of type styles, tension means adapted to maintain the type basket either in a forward or rearward position on the frame in respect to the platen to maintain one of the type styles in an operative position in respect to the printing point, said means including a pair of springs, and means for putting one or the other under tension for the aforesaid purpose; a lever to move the type basket on 105 the frame against the tension of the spring already under tension and shift the position of registration of the lower case character of said operative style to another in respect to the printed point on the platen, 110 and a lever mounted on the frame adapted to move the platen so as to shift the printing point from the registrability of the upper case character of said operative style to the lower case character.

10. A typewriter comprising a frame, a platen supported by the frame, a type basket supported by the frame, a type bar carried by the basket having printing characters in a plurality of type styles, a shift lever mounted on the frame and having two shoulders, a rocker pivotally mounted on the frame, having a connection to the type basket, and a link at each end hanging into proximity with the shoulders; means to shift the links so that one or the other comes beneath a shoulder to cause a forward or rearward movement of the type basket upon depression of the lever to correspondingly change the style of type in registra- 115 120 125 130

- tion with the printed point on the platen, and means associated with the rocker to hold the links in an adjusted position and the type basket in the corresponding position.
- 5 11. A typewriter having a platen, a type basket, a plurality of type bars divided into front and rear segments in respect to the platen, printing characters in a plurality of type styles carried by the type bars, those in the front segment having the order of upper and lower case characters reading downwardly and those in the rear segment having the order of lower and upper case characters reading downwardly, and means to
- 10 shift the type basket in respect to the platen to bring the lower case characters of a desired type style into registration with the printing point.
12. A typewriter having a platen, a type basket, a plurality of type bars divided into front and rear segments in respect to the platen, printing characters in a plurality of type styles carried by the type bars, those in the front segment having the order of upper and lower case characters reading downwardly and those in the rear segment having the order of lower and upper case characters reading downwardly, means to
- 15 shift the type basket in respect to the platen to bring the lower case characters of a desired type style into registration with the printing point, and means for shifting the platen in respect to the type basket to bring the upper case characters of a desired type
- 20 style into registration with the printing point.
13. A typewriter having a frame, a platen movably supported by the frame, a type basket movably supported on the frame, a plurality of type bars carried by the type basket and divided in front and rear segments in respect to the platen, printing characters in a plurality of type styles carried by the type bars the characters on the bars in the front segment having upper and lower case type reading downwardly, those in the rear segment having lower and upper case type reading downwardly, and separate means having individual operating connections to both the platen and type basket adapted to be depressed to simultaneously shift the platen and type basket in one direction to print upper case characters of a style different from that capable of being printed under the normal adjustment of the typewriter.
14. A typewriter comprising a platen, a type basket, type bars carried by the basket, upper and lower case printing characters carried by the bars in a plurality of type styles of which the lower case characters of one style are in normal registration with the printing point, and separate means having independent connections with the platen and type basket adapted to be depressed together to move the platen and the type basket to simultaneously shift the printing point and bring the upper case characters of another type style in registration therewith.

JOEL SMITH.
